SUNSHADE

Lewis A. Vesta, Boyd, Minn.

Application November 6, 1941, Serial No. 417,999

1 Claim. (CL 296—44)

My invention relates to sunshades and has for an object to provide a sunshade which may be easily and quickly attached to a motor vehicle to shield the occupants from the rays of the sun entering the windows in the body of the motor vehicle and to prevent rain from entering the open windows.

An object of the invention resides in providing a sunshade which can be securely attached to the motor vehicle.

Another object of the invention resides in providing a sunshade which can be attached to either the upper rail of the door of the motor vehicle or to the gutter of the motor vehicle.

An object of the invention resides in providing a sunshade having a mounting for attachment to the motor vehicle and a shield pivotally supported by said mounting.

A feature of the invention resides in providing a frictional means engaging a part movable with the shield for holding the shield in adjusted position.

Another object of the invention resides in providing the shield with a shaft attached thereto and rotatably mounted in the mounting and in providing friction means for engaging the shaft.

A still further object of the invention resides in constructing the mounting as a case having a front wall and a rear wall and end walls and open at the top and in rotatably mounting said shaft in the end walls of the case with a portion thereof accessible from the interior of the case.

A still further object of the invention resides in arranging the friction means within the case and in engagement with the portion of the shaft within the case and in further providing adjusting means extending through the case for varying the pressure of the friction means on the shaft.

A feature of the invention resides in providing a clamp member having a jaw spaced from and parallel to the rear wall of the case and movable toward and from said rear wall to clamp the case upon the lip of a door or gutter of the vehicle.

A feature of the invention resides in providing the clamping member with a flange overlying the upper edge of the rear wall and an ear extending inwardly therefrom through the open end of the case and in further providing a screw extending through the front wall of the case and engaging said ear to move the jaw of the clamp member toward and from the rear wall of the case.

Other objects of the invention reside in the novel combination and arrangement of parts and in the details of construction hereinafter illustrated and/or described.

5 In the drawings:

Fig. 1 is an elevational view of a portion of the motor vehicle illustrating an embodiment of my invention applied to the door of the same.

Fig. 2 is an elevational sectional view taken on line 2—2 of Fig. 1 and drawn to a greater scale.

Fig. 3 is an elevational sectional view taken on line 3—3 of Fig. 2.

Fig. 4 is a view similar to Fig. 2 taken on line 4—4 of Fig. 3.

15 Fig. 5 is a view similar to Fig. 2 showing the sunshade attached to the gutter of a motor vehicle.

Fig. 6 is a perspective view of the parts of the mounting detached from one another.

20 In driving motor vehicles in sunny weather, considerable inconvenience is encountered when the sun shines inwardly through the side windows of the motor vehicle and upon the passengers. Heretofore devices used for the purpose of shading the occupants have required reconstruction of the motor vehicle. In other cases, the application of the shade to the motor vehicle has left spaces between the shade and body of the vehicle through which the sun might

25 shine upon the occupants. The present invention overcomes these difficulties by providing a sunshade which may be easily and quickly attached to existing parts of the motor vehicle without alteration or reconstruction thereof and

30 which completely shades the occupants from the sun directed toward the window to which the sunshade is applied.

For the purpose of illustrating the application of my invention, I have shown in the drawings a portion of a motor vehicle 10. The body of the vehicle is designated by the reference numeral 11 and includes a top 12 and a number of doors 13 and 14. Immediately above the doors 13 and 14 is a gutter 15.

35 A portion of the door 13 is shown in cross section in Fig. 2. This portion of the door consists of two molded parts 16 and 17 which are spaced from one another to receive therebetween a channel 18 having a felt liner 19 therein. This liner is constructed with a groove 21 in which the window pane 22 of the door is received. The two molded portions 16 and 17 are connected together by means of a connecting strip 23 which is formed with a depending flange 24 secured to the member 17 and with an up-

wardly extending flange 25 overlying the outer portion 26 of the member 16. This construction forms a lip projecting outwardly from the door proper, indicated at 30. The portion 26 of member 16 is turned over upon the flange 25 as designated at 27 to form a bead at the outermost edge of the lip 30. A gasket 13 is attached to the connecting strip 23 and overlies the lip 30. The construction described provides an upper rail 28 and stiles 29 connected therewith. The various parts of the door are preferably constructed of metal and are welded or otherwise secured together.

The gutter 15 of the motor vehicle is secured to the top by welding or otherwise and has an outer curved wall or lip 31 and an interior wall 32 spaced therefrom and forming with the wall 31 a trough 33 in which the water is collected. The wall 32 is welded or brazed to the top 12 and is thus rigidly secured thereto.

The invention proper consists of one or more mountings, two of which are shown in Fig. 1 and indicated by the reference numerals 34 and 34^a. Since both of these mountings are identical, only the mounting 34 will be described. Rotatably connected to these mountings is a shield 35 which may be swung from its uppermost position, as shown in dotted lines in Fig. 4, or to a number of other operating positions, such as shown in full lines in said figure. The mounting 34 includes a clamping member 36 which cooperates with said mounting to hold the mounting attached to the door or gutter of the motor vehicle. These parts will now be described in detail.

The mounting 34 consists of a case 37 having a front wall 38, a rear wall 39 and end walls 41 and 42 connected therewith. Said case is open at the top, but is closed at the lowermost portion of the same by means of a bottom 43. These walls form a compartment 40 within the case. The front wall 38 is constructed at the lowermost portion of the same with an offset 44 semi-circular in cross section, which provides an under cut space 45 within the same communicating with the compartment 40.

The shield 35 has been illustrated in the case as constructed of metal, though it can be readily comprehended that any other material, such as is now well known in the art may be employed. The shield 35 is provided at the innermost end with looped portions 46 which encircle a shaft 47 supporting the said shield. The shaft 47 extends through the walls 41 and 42 of case 37 and is journaled in suitable bearings 48 formed therein, having a portion 52 thereof disposed within the space 45 of said case. At the locality of the case 37, the shield 35 is notched as indicated at 49 to receive the portion 44 of said case and to permit of swinging of said shaft and shield relative to said case. The shield 35 is attached to the shaft 47 by means of a pin 51 or otherwise, so that said shaft rotates relative to the case 37 with the shield 35.

The shield 35 is held in adjusted position by means of a spring friction member 55, best shown in Figs. 3 and 4. This friction member is constructed from a strip of spring material, which is bent to provide a loop 56 adapted to encircle the portion 52 of shaft 47. The loop 56 is open and has two arms 57 and 58 connected with the ends thereof, said arms issuing outwardly therefrom in spaced relation to one another. The loop 56 is disposed in the under cut space 55, 75

while the two arms 57 and 58 extend into the compartment 40. The arm 57 engages the innermost surface of the wall 38, while the arm 58 is parallel therewith. Formed in the center of the front wall 38 of case 37 is a counter-sunk hole 59, best shown in Fig. 6. A counter-sunk machine screw 61 extends through this hole and through similar holes 62 in the arms 57 and 58 of the friction member 55. This screw engages a nut 63 disposed upon the rear surface of the arm 58, which nut is held from rotation by means of a lug 64 bent outwardly from said arm. It will readily be comprehended that rotation of the screw 61 in one direction will draw the arms together and cause pressure to be exerted by the loop 56 on the portion 52 of shaft 47, whereby friction is produced tending to hold the shield 35 in adjusted position. Upon rotating screw 61 in the opposite direction, the resiliency of the arms 57 and 58 causes the arms 57 and 58 to spring away from one another and the loop 56 to release the shaft and to reduce the pressure thereon. By means of said screw, the friction may be adjusted so that any degree of resistance to the movement of the shield within the limits of the device may be procured.

The mounting 37 is held attached to the lip 30 of the door 13 by means of the clamping member 36 which is best shown in Figs. 2 and 6. This clamping member is preferably constructed from sheet metal and is formed with a jaw 65 and with a flange 66 issuing outwardly therefrom. Extending outwardly from the flange 66 are two spaced ears 67 and 68 which are threaded at 69 to receive screws 71. The jaw 65 is disposed outwardly of the rear wall 39 of the case 37 which serves as another jaw and is arranged in parallel relation thereto. The flange 66 overlies the upper edge of the rear wall 39, while the ears 67 and 68 extend into the compartment 40 of case 37 through the open upper end thereof and straddle the friction member 55. The screws 71 are received in counter-sunk holes 72 formed in the front wall 38 of case 37 which are disposed on opposite sides of the holes 59. Upon rotation of the screws 71, the ears 67 and 68 may be drawn toward the front wall 38 and the jaw 65 moved toward the jaw 39. The jaw 65 is constructed with a ridge 74 which is adapted to engage beneath the bead 27 and to directly engage the flange 25 of the connecting member 23. Thus the jaw 65 engages both the said bead and flange to securely hold the mounting attached to the door of the motor vehicle. In order to prevent marring of the paint upon the outer surface of the rim 30, a gasket 75 is employed which is attached to the exposed surface of the jaw 39.

The method of using the invention is obvious. The jaw 65 is first moved outwardly from the jaw 39 a distance sufficient to permit of insertion of the lip 30 into the space between said jaws. In the application of the clamping member 36 to the door, the gasket 13 is first moved away from the lip 30 to permit of insertion of the jaw 65 therebetween. The two screws 71 are next tightened until the clamping member is brought into engagement with the rim of the door and until the jaws securely clamp the mounting to the same. Both mountings are similarly applied. After the sunshade has been mounted, the screws 61 are tightened until the desired amount of friction is had to hold the shield in proper position. When the device is in use, the shield may be manually shifted in position to give the desired shading effect. One of the operating posi-

tions of the shield is shown in full lines in Fig. 4. When it is desired to swing the shield out of the way, the same is moved upwardly until it reaches the position shown in dotted lines in Fig. 4. The thickness of the jaw 65 being relatively thin, the same offers no difficulty in the closing of the door, since doors for motor vehicles are provided with ample space for the purpose.

By means of the construction shown, the mounting may be also attached to the outer wall or lip 31 of the gutter 15. For this purpose, the jaw or rear wall 39 of the case 37 is formed with a groove 76 which conforms in shape to the curvature of the wall 31 of gutter 15. The gasket 75 follows along this groove. The ridge 14 on the clamp jaw 65 is directly opposite the groove 76, so that the same engages the wall 31 of the gutter on the inner surface thereof and the gasket 75 is held in engagement with said wall at the groove 76. The method of application of the invention to the gutter 15 is the same as to the door 13.

The advantages of my invention are manifest. The device is extremely practical and simple in construction and may be easily and quickly applied to existing motor vehicles. Due to the fact that the device may be attached to the gutter of the motor vehicle, the same may be applied so as to shade the windows of the motor vehicle not mounted in the doors thereof, as for example, the rear side windows of a sedan or coach. The shade may be shifted from one door to the other and when applied to the gutter, may be moved along the gutter to occupy different positions with respect to the windows of the motor vehicle. The shield is easily moved by simple manual manipulation from operative to inoperative position and vice versa. The principal

operating parts of the device are contained within the case forming the mounting, where the same are protected from injury. My improved sunshade is neat and attractive in appearance and occupies a minimum amount of space in storage.

Changes in the specific form of my invention, as herein disclosed, may be made within the scope of what is claimed without departing from the spirit of my invention.

Having described my invention, what I claim as new and desire to protect by Letters Patent is:

A sunshade comprising a case having a front wall, a rear wall, a bottom, and end walls connected thereto, a shaft extending through the end walls of the case and rotatably mounted therein, said shaft being located in the corner between said front wall and bottom, a shield attached to said shaft, friction means within the case comprising a band encircling the shaft and having upwardly extending arms, said arms being disposed intermediate the end walls of the case, a screw extending through the front wall of the case and engaging one of said arms for drawing the arms together to produce friction between said band and shaft, a clamping member having ears extending into the case and disposed on opposite sides of said arms, screws extending through the front walls of the case and engaging said ears, said screws straddling said first named screw, all of said screws being disposed above said shaft, a jaw on said clamping member cooperating with the rear wall of the case to clamp an object therebetween, and means extending through the case and connecting said jaw to said ears.

LEWIS A. VESTA.
